(57) **CLAIM**

The ornamental design for a webcam cover, as shown and described.

DESCRIPTION

FIG. 1 is a front and top perspective view of a webcam cover in a closed configuration to cover a webcam of an electronic device;

FIG. 2 is a front elevational view thereof;

FIG. 3 is a top plan view thereof;

FIG. 4 is a bottom plan view thereof;

FIG. 5 is a right elevational view thereof;

FIG. 6 is a left elevational view;

FIG. 7 is a rear elevational view thereof; and,

FIG. 8 is a front and bottom perspective view thereof in an exploded configuration showing the slider isolated from the base.

The broken lines shown in the drawings depict environmental subject matter, specifically an electronic device in FIG. 1, and portions of the webcam cover that form no part of the claimed design.
